SHEET BINDING MEANS

Frederick J. Perry, Sr., North Arlington, N. J.

Application January 15, 1944, Serial No. 518,369

2 Claims. (Cl. 281—21)

This invention relates to improvements in sheet binding means; and the invention has reference, more particularly, to a novel construction of binding device especially useful for binding together the cover and loose inner leaves of sheet music.

The invention has for an object to provide a novel binding device comprising a series of independent leaf embracing and holding elements, each longitudinally folded upon itself to provide a tubular hinge barrel, said elements being longitudinally aligned, end to end, along a common hinge pin element, which extends through their hinge barrels, whereby outer and inner leaves or sheets may be embraced by and secured between the sides of selected holding elements so as to be capable of being independently turned about the hinge pin element, and yet securely connected or bound together against separation one from another with risk of loss or misplacement from their properly associated relationship.

The invention has for another object to provide a binding device of the kind above referred to in which the leaf embracing and holding elements are made of rigidulous sheet material, such e. g. as thin sheet Celluloid or the like, and in which the hinge pin element is made of a somewhat resilient material, such e. g. as textile or other cord which has been stiffened by a suitable sizing so as to be sufficiently flexible without being flimsy, whereby the same is not easily subject to permanent distortion from a normal straight condition; means to be provided in connection with terminal members of the leaf embracing and holding elements for retaining the hinge pin element against displacement from operative association with the series of leaf embracing and holding elements served thereby.

Other objects of this invention, not at this time more particularly enumerated, will be understood from the following detailed description of the same.

An illustrative embodiment of the novel sheet binding means according to this invention is shown in the accompanying drawing, in which:

Fig. 1 is a front face view of a piece of sheet music the outer and inner leaves of which have been hingedly bound together by the novel binding means of this invention; Fig. 2 is a fragmentary rear face view of the same; Fig. 3 is a fragmentary face view of the sheet music with its front cover leaf opened and its inner leaf exposed; Fig. 4 is a fragmentary face view of the opened sheet music showing its inner leaf turned; and Fig. 5 is a fragmentary perspective view showing the terminal members of the leaf embracing and

holding elements of the binding means, and the means provided in connection therewith for retaining the hinge pin element against displacement.

Similar characters of reference are employed in the herein above described views, to indicate corresponding parts.

Referring to the drawing, the illustrative embodiment of the sheet binding means is shown as operatively applied to a piece of sheet music comprising a front leaf or sheet 10, an inner leaf or sheet 11, and a back leaf or sheet 12.

The sheet binding means comprises, in the illustrative form thereof as shown, terminal leaf embracing and holding elements 15, and intermediate leaf embracing and holding elements 16 and 17. Each leaf embracing and holding element comprises a bifurcate structure formed by a tubular hinge barrel portion 18 and a pair of wing sections 19 extending therefrom. Each such embracing and holding element is made of rigidulous sheet material, such e. g. as thin sheet Celluloid or the like, which can be shaped and set to provide the tubular hinge barrel portion 18.

Said leaf embracing and holding elements 15, 16 and 17 are longitudinally aligned, end to end, upon and along a common hinge pin element 20, disposed to extend through their hinge barrel portions 18, whereby the leaf embracing and holding elements 15, 16 and 17 may freely turn about said hinge pin element 20 as an axis. The hinge pin element 20 is of somewhat less length than the total length of the end to end aligned leaf embracing and holding elements, and to retain,

said hinge pin element against longitudinal displacement from its operative assembled relation to said leaf embracing and holding elements, the outer ends of the barrel portions of the terminal leaf embracing and holding elements, are pinched and set together to provide a barrel passage closure portion 21, by which the respective ends of the hinge pin element 20 is stopped so as to arrest longitudinal shifting displacement thereof.

The hinge pin element 20 is of rod-like form and is made of a somewhat resilient or springy non-metallic material. For example, the same may comprise a non-metallic cord or rod of inherently resilient material, or a textile cord which has been stiffened by a suitable sizing substance so as to be sufficiently flexible without being flimsy. A resilient cord or rod of such characteristic is desirable so that it may flex without being subject to permanent bending or distortion from its normal straight condition, and consequently is not subject to risk of bending out of shape so

as to distort the flat spreading condition of the music sheets served by the binding means, or to the risk of jamming the leaf embracing or holding elements against free turning or swinging movement about the same.

To apply the novel binding means to the music sheets, front and back sheets 10 and 12 of the sheet music to be bound are separated, whereupon said front sheet 10 is inserted between the wing sections 19 of the respective terminal leaf embracing and holding elements 15, and the inner faces of said wing sections are adhered by a suitable adhesive to said front sheet 10. The back sheet 12 is then inserted between the wing sections 19 of the respective leaf embracing and holding elements 16 next adjacent to the terminal elements 15, and the inner faces of said wing sections are likewise adhered by a suitable adhesive to said back sheet 12. Finally the intermediate or inner sheet 11 is inserted between the wing sections 19 of the middle or remaining leaf embracing and holding element 17, and, in like manner said wing sections are adhered by a suitable adhesive to said inner sheet 11.

The adhesive employed to secure the music sheets to and between the wings 19 of the holding elements may be applied at the time of carrying out the binding operation, or, if desired, the inner faces of said wings 19 may be provided with a dry adhesive coating 22 (see Fig. 5) which can be moistened for use at the time of performance of the binding operation.

Although the double wing form of the holding elements shown and described is preferable, it will be understood that one of the wings may be omitted if desired and but a single wing provided for adherence to the leaves or sheets to be bound.

It will also be understood that the order in which the holding elements are adhered to the successive leaves or sheets to be bound may be varied from that above described as may be deemed most expedient to the user of the binding device; furthermore, it will also be clear that the number and length sizes of the holding elements may also be varied within reasonable limits, and according to the total number of leaves or sheets to be accommodated. For the ordinary three leaf form of sheet music the described number and relative arrangement of holding elements will probably be found the most satisfactory.

The novel binding means according to this invention serves admirably to hold in proper associated relation the successive leaves or pages of sheet music; and in such manner that the music will be retained in flat lying or spread condition either open or closed, while nevertheless the sev-

eral leaves or pages may be easily, freely and independently turned about a common hinge axis. The hinge pin element being resilient, will not take a permanent bend so as to either distort the plane of the leaves or pages, or obstruct the free swinging turning thereof, and yet, since the hinge pin element extends substantially throughout the length of the sheet music, the latter cannot be accidentally folded or crumpled transversely, and consequently is kept in good condition and its useful period of life is therefore substantially prolonged.

I am aware that some changes could be made in the above described constructions without departing from the scope of this invention as defined by the following claims. It is therefore intended that all matter contained in the foregoing description or shown in the accompanying drawings shall be interpreted as illustrative and not in a limiting sense.

I claim :

1. Sheet binding means comprising a series of independent leaf holding elements arranged end to end, each holding element being formed from rigidulous sheet material to provide a longitudinal hinge barrel and a pair of opposed wing sections projecting laterally therefrom, inner marginal portions of successive leaves to be bound being adapted to be inserted between and adhered to the wing sections of selected holding elements, a hinge pin element of resilient material common to and extending through the hinge barrels of the aligned holding elements whereby the latter may turn independently thereon, and the terminally disposed holding elements having means to close the outer end portions of their hinge barrels against longitudinal displacement of the hinge pin element relative to the series of holding elements hinged thereon.
2. Sheet binding means comprising a series of independent leaf holding elements arranged end to end, each holding element comprising a body of sheet material having a longitudinal tubular hinge barrel integral therewith, interior marginal portions of successive leaves to be bound being secured to the bodies of selected holding elements, a hinge pin element of resilient material common to and extending through aligned hinge barrels of the holding elements whereby the latter may turn independently thereon, and the terminally disposed holding elements having means to close outer end portions of their hinge barrels against longitudinal displacement of the hinge pin element relative to the series of holding elements hinged thereon.

FREDERICK J. PERRY, SR.
